UNITED STATES PATENT OFFICE.

JAMES BOWEN, OF LINDEN, MICHIGAN.

BAG-FILLING DEVICE.

1,014,998.

Specification of Letters Patent.

Patented Jan. 16, 1912.

Application filed April 29, 1911. Serial No. 624,148.

To all whom it may concern:

Be it known that I, JAMES BOWEN, citizen of the United States, residing at Linden, in the county of Genesee and State of Michigan, have invented certain new and useful Improvements in Bag-Filling Devices, of which the following is a specification.

The present invention is in the nature of a machine for filling bags or similar containers with cement, sand, or the like, and the primary object of the invention is the provision of a machine of this character which embodies novel features of construction whereby the flow of cement or like material into the bag is automatically shut off as soon as the required weight of material has entered the bag.

A further object of the invention is the provision of a bag filling machine which is simple and inexpensive in its construction, which will enable a large number of bags to be filled with a minimum amount of labor and in a comparatively short period of time, and which comprises few and durable parts well adapted to withstand the usual rough usage without continually getting out of repair or adjustment.

With these and other objects in view as will more readily appear as the description proceeds, the invention consists in certain novel combinations and arrangements of the parts, the novel features thereof being pointed out in the appended claims.

For a full understanding of the invention, reference is to be had to the following description and accompanying drawings, in which:

Figure 1 is a longitudinal sectional view through a bag filling machine constructed in accordance with the invention. Fig. 2 is a top plan view of the same. Fig. 3 is a vertical sectional view through the hopper on the line 3—3 of Fig. 1. Fig. 4 is a horizontal sectional view on the line 4—4 of Fig. 1. Fig. 5 is a horizontal sectional view through the upper end of the bag holding frame, taken on the line 5—5 of Fig. 1. Fig. 6 is a top plan view of a modified construction of the bag holding frame. Fig. 7 is a view similar to Fig. 5 showing a modified form of bag engaging members employed for engaging the mouth of a cloth bag, and Fig. 8 is a sectional view on the line 8—8 of Fig. 7.

Corresponding and like parts are re-

ferred to in the following description and indicated in all the views of the drawings by the same reference characters.

Specifically describing the present embodiment of the invention, the numeral 1 designates the base upon which a suitable superstructure is mounted, the said superstructure including a platform 2 which is arranged over the base and projects beyond one end thereof. The weighing device or scales 3 are mounted upon the base 1, and are shown as comprising a pair of spaced beams suitably connected by brace members and provided at intermediate points in their length with the downwardly opening V shaped notches 4 receiving a knife blade 6 projecting upwardly from the base. The weight 6 has one end thereof pivotally mounted upon the end of the scales 3, while the opposite end thereof is adjustably engaged by a rod 7 which is pivotally connected to the scales at an intermediate point in the length thereof. This rod 7 is shown as threaded and extending through an opening in the weight 6, nuts 8 being mounted upon the rod and engaging opposite sides of the weight so as to hold the weight in an adjusted position. With this construction it will be apparent that the weight can be swung up or down and locked in any desired position, the effect of the weight being increased as it is swung upward, and decreased as it is swung downward. The opposite end of the scales 3 is provided with the upwardly opening V shaped notches 9 receiving a knife blade 10 at the lower end of a bag supporting frame 11, the upper end of the said bag supporting frame being loosely connected to the elevated platform 2 by means of the links 12. These links 12 do not interfere in any manner with the free up and down movement of the bag supporting frame, but merely serve to maintain the same in an upright position. The bag supporting frame itself is formed with a lower shelf 13 upon which the bottom of the bag 14 is designed to rest, and also with a head 15 which is arranged over the shelf 13 and is provided with means for engaging the mouth of the bag. It will also be observed that the head is formed with a central opening 16 through which the bag may be filled with cement or other material, as may be desired.

A hopper 17 is mounted upon the projecting end of the platform 2 and is provided

in the bottom thereof with an opening 18 which registers with a similar opening 19 formed in the platform 2 and arranged directly over the opening 16 in the head of 5 the bag supporting frame. Any suitable form of agitator such as that indicated at 20 may be arranged within the hopper 17 to cause a proper feeding of the cement or other material within the hopper. The bottom 10 of the hopper is arranged above and slightly spaced from the platform 2, a slide 21 being mounted within the space between the two members. This slide is formed at the outer end thereof with an opening 22 15 which can be moved either into or out of registry with the openings 18 and 19 to permit a flow of cement from the hopper through the said openings, or shut off the flow of cement through the said openings. 20 The opposite end of the slide is shown as engaged by suitable guide members 23, and also by a spring 24 which normally tends to push the slide outwardly so as to shut off the flow of cement. A longitudinally 25 disposed slot is formed in the slide, and a pawl 25 is mounted within this slot, the rear end of the pawl being pivoted at 26 between the side walls of the said slot, while the forward end of the pawl is flared and normally 30 tends to drop by gravity into such a position as to project downwardly below the bottom of the slide, the downward movement of the pawl being limited by a lip 27 which projects from the upper end thereof 35 and is designed to engage the top of the slide. This pawl is designed to engage a notch 28 in a detent 29 which is arranged within a slot 30 in the platform 2 and is rigid with a transversely disposed shaft 31. 40 An arm 32 projects laterally from one end of the shaft 31 and is connected by an upper right link member 33 to the scales 3.

When the bag 14 is empty or partially filled and is over balanced by the weight 45 6, the shaft 31 is suitably rotated to bring the detent 29 into the position shown in Fig. 1 so that the notch 30 therein will be engaged by the pawl 25 when the slide 21 is moved rearwardly against the action of the 50 spring 24. In this connection, it will be obvious that when the slide is moved rearwardly the pawl 25 will be swung upwardly by engagement with the back of the detent 29 until the slide reaches the position shown 55 in Fig. 1, with the opening 22 therein in alignment with the opening 18 of the hopper, when the nose of the pawl will drop by gravity into the notch 28. The cement or other material within the hopper 17 will 60 then flow into the bag 14 until a sufficient amount thereof has entered the bag to overcome the action of the weight 6. The scales will then tilt and thereby pull downwardly upon the link 33 so as to rotate the shaft 31 65 and revolve the detent 39 into such a position

as to disengage the pawl 25 from the notch 28 and release the slide 21. The spring 24 will then force the slide outwardly so as to shut off the flow of cement from the hopper. The bag can then be removed from the bag holding frame and another bag applied thereto, after which the slide 21 will again be moved rearwardly into the position shown in Fig. 1, either manually or by any suitable mechanical means provided for that purpose.

When the machine is utilized in connection with paper bags, as indicated in Figs. 1 and 5, the head 15 of the bag supporting frame will be formed with a downwardly 80 projecting annular flange 34 adapted to have the mouth of the bag clamped thereto. Any suitable means may be provided for this purpose, such as the curved levers 35 shown in Fig. 5, the rear ends of the said levers 85 being pivoted at 36 to the head, while the forward ends of the levers are extended outwardly at 37 so as to be detachably connected. In the present instance one of the extensions 37 is provided with a spring 28 90 provided with a hook 39 adapted to engage an eye 40 in the opposite extension. With this construction it will be obvious that the clamping levers 35 can be quickly drawn together so as to engage the mouth of a bag 95 and hold it in proper position, or separated to release the mouth of the bag.

A modification adapted to be employed in connection with bags made of cloth or fabric is shown in Figs. 6, 7 and 8. In this construction a pair of substantially semi-circular bag engaging members 41 are applied to the bottom of the head 15, the intermediate portions of the members 41 being suitable notched at 42 to provide a clearance 100 for the opening 16, and one end of the said members 41 being pivoted to the head 43, while the opposite end of each of the said members is formed with a curved wall 44 adapted to be engaged by a double cam 45. This cam is mounted upon a shaft 46 which projects upwardly through the head 15 where it is provided with a handle 47. When this handle is turned into the position indicated in Fig. 6, the bag engaging members 41 can swing together so that the mouth of a bag can be readily drawn over the same or removed therefrom. However, when the handle 47 is turned into the position indicated in Fig. 7 so as to throw the double cam member 45 into engagement with the curved walls 44, the members 41 will be forced apart, as indicated in Figs. 7 and 8, so as to engage the mouth of a bag and hold the bag securely in position.

While I have employed a single one of these bag filling machines, yet it is contemplated in practice to provide a series of these machines upon a single support, and it will be obvious that such is entirely within the 130

scope of the invention. Under some conditions it may be found desirable to make some provision for the escape of air from the bags as the cement enters the same, and 5 for this purpose air pipes 50 are shown upon opposite sides of the hopper, the lower end of the air pipes being in communication with the mouth of the bag while the bag is being filled.

10 Having thus described the invention, what I claim as new and desire to secure by Letters Patent, is:—

1. In a bag filling device, the combination of tilting scales, a bag supporting frame mounted upon the tilting scales, a hopper arranged over the bag supporting frame so as to feed material into a bag mounted thereon, a slide for shutting off the flow of material from the hopper, yielding 20 means normally tending to move the slide into operative position, a pawl mounted upon the slide, a rotary detent adapted to engage the pawl to lock the slide in an inoperative position, a rock shaft carrying the 25 rotary detent and provided with a crank arm, and a link member connecting the crank arm to the tilting scales for rotating the rock shaft and releasing the detent when the scales are tilted.

30 2. In a bag filling device, the combination of tilting scales, a bag supporting frame mounted upon the tilting scales, a hopper arranged over the bag supporting frame so as to feed material into a bag mounted 35 thereon, a slide for shutting off the flow of material from the hopper, yielding means normally tending to move the slide into operative position, a pawl mounted upon the slide and normally tending to drop by 40 gravity into such a position as to project below the slide, a rock shaft mounted under the slide, a rotary detent carried by the rock shaft and formed with a notch adapted to be engaged by the downwardly projecting end of the pawl to hold the slide in 45 an inoperative position, and an operative connection between the rock shaft and the scales for releasing the detent from engagement with the pawl when the scales are 50 tilted.

3. In a bag filling device, the combination of tilting scales, a bag supporting frame mounted upon the scales, an elevated platform arranged over the scales, a hopper 55 mounted upon the platform and disposed over the bag supporting frame so as to feed into a bag mounted upon the same, a slide mounted upon the platform and adapted to cut off the flow of material from the hopper, 60 the said slide being formed with a slot, yielding means normally tending to move the slide into operative position, a wedge shaped pawl having the reduced end there-

of pivoted within the slot, the opposite end of the pawl being designed to drop by 65 gravity into such a position as to project below the slide and being formed with a lip projecting over the top of the slide to limit the downward movement thereof, a rock shaft mounted upon the elevated platform, 70 a detent mounted upon the rock shaft and formed with a notch adapted to be engaged by the pawl to hold the slide in an inoperative position, and an operative connection between the rock shaft and the scales for 75 automatically releasing the slide when the scales are tilted.

4. In a bag filling device, the combination of tilting scales, a fixed superstructure arranged over the tilting scales, an upright 80 bag supporting frame having the lower end thereof pivotally connected to the scales, the said bag supporting frame being formed with a lower shelf adapted to engage the bottom of the bag and also with an upper 85 head having an inlet opening therein, means upon the said upper head for engaging the mouth of a bag, a link pivotally connecting the bag supporting frame to the superstructure for holding the bag supporting 90 frame in an upright position, a hopper mounted upon the fixed superstructure and adapted to discharge through the inlet opening of the upper head into the bag, and means for automatically cutting off the flow 95 of material from the hopper when the scales are tilted by the weight of the material in the bag.

5. In a bag filling device, the combination of tilting scales, a fixed superstructure 100 arranged over the tilting scales, an upright bag supporting frame having the lower end thereof pivotally connected to the tilting scales, the said bag supporting frame being formed with a lower shelf for engaging the 105 bottom of the bag, and also with an upper head having an inlet opening and an air outlet opening therein, a link pivotally connecting the bag supporting frame to the superstructure for holding the said bag supporting frame in an upright position, a hopper mounted upon the superstructure and adapted to discharge through the inlet opening of the upper head into the bag, an air outlet member upon the superstructure 110 registering with the air outlet of the said upper head, and means for cutting off the flow of material from the hopper when the scales are tilted by the weight of the material in the bag.

115 In testimony whereof I affix my signature in presence of two witnesses.

JAMES BOWEN.
